METHOD OF APPLYING FACING MATERIAL

Alfred H. Parsons, Rockville Centre, N. Y.

Application July 10, 1936, Serial No. 89,923

10 Claims. (Cl. 72—19)

This invention relates to improved methods of applying facing material to supporting structure.

The present application is a continuation in part of my copending application Serial No. 4,19,818, filed May 4, 1935, for Method of veneering.

Heretofore, facing material of various types has been applied to supporting structures, successfully, in only the conventional manner. That is, in brick veneering and stone veneering it has been found necessary to use brick of ordinary dimensions or stone of proportionate thickness with the brick or stone bonded together in the usual fashion and tied to the supporting structure at intervals. Efforts have been made to utilize brick of less than usual dimensions but, so far as applicant is aware, such efforts have failed. Moreover, in the application of tile and the like to supporting structures it has been customary to set the tile in a heavy supporting mass of cement, mortar, or the like, with the result that the tile is of necessity spaced some distance from the supporting structure. Since this arrangement does not permit efficient tying of the tile to the supporting structure, the life of the assembly is materially shortened.

An object of the present invention is to provide improved methods for applying facing material of various types to supporting structures.

30 A further object of the invention is to provide methods as set forth hereinbefore, wherein each unit of the facing material is more or less independently tied to the supporting structure.

In carrying out the foregoing and other objects of the invention, use is made of anchoring means comprising primary anchoring devices and secondary anchoring devices. In the practice of the invention the primary anchoring devices are first secured to the supporting structure at pre-determined spaced intervals, then the facing material is applied with the assistance of the secondary anchoring means to become firmly held to the supporting structure. During the application of the facing material use is made of mortar or other bonding material in the usual fashion. The facing material, made up usually in the form of relatively thin units, has certain of the edges thereof provided with formations which cooperate with the anchoring means to hold the units to the supporting structure. In one form of the invention the facing units are made substantially in the form of brick of a thickness considerably less than that of conventional brick. Certain of the edges of these units can be provided with formations, either ex-

tending to one face of the unit, or included wholly within the edges thereof.

In another form of the invention it is contemplated that units may be made of relatively large size but of relatively thin thickness, such units also having cooperating formations to be engaged by certain of the anchoring means. The units may be made of any desired material, such as baked clay (ordinary brick), stone or any desired pre-formed composition.

10 In another form of the invention the units are in the general shape of usual ceramic tile and again such units have formations in certain of the edges thereof to cooperate with the anchoring means.

15 Other features, objects and advantages of the invention will become apparent from the following detailed description of the accompanying drawings, wherein:

Fig. 1 is an isometric view of the corner of a 20 building showing brick veneering according to the present invention in various stages of application;

15 Fig. 22 is a horizontal section showing the manner of application of certain units for corner construction.

Referring to the drawings and more particularly to Figs. 1 and 2, the reference character 10 indicates an improved facing unit or brick which is preferably formed with its exposed face having the same dimensions as the side of a conventional brick. The brick is made relatively thin, the preferred thickness being about three-quarters of an inch. The rear face 12 of the brick is larger than the front face 11, and each side has a straight bevel as illustrated in Fig. 1. This brick is made of any preferred material, such as ordinary brick clay, and the face may be given any desired texture or design. The reduced volume of the brick will result in considerable savings in the cost of manufacturing and handling the bricks.

As shown in Fig. 2, the parts of the building frame are arranged so that the outer surface of the sheathing is flush with the outer surface of the foundation. After the sheathing has been covered with tar paper, as the first step in applying the veneering, the courses of primary anchoring devices or nails that are to support the veneering bricks are driven into the sheathing. The nails 13, which are of a well-known double-headed construction, have an outer head 14 and a lower head 15 spaced inwardly from the outer head. The nails are preferably formed of copper or some other rust-proof material. The first row of nails 16 is arranged parallel to the bottom edge of the sheathing and at a distance from said edge slightly greater than the width of the rear face of a brick. The nails of this row are spaced from each other such a distance that each whole brick will be supported by two nails. With bricks having a face 8" x 2" the nails should be spaced about 3 $\frac{1}{4}$ " apart and the first nail should be about 2 $\frac{1}{2}$ " from the corner of the building.

55 After the first horizontal row 16 of nails has been established the vertical row 17, which is the second row from the corner of the building, is next established. The vertical lines of the building framework are practically never perfectly plumb for any one of a number of reasons, and it is essential that the vertical rows of nails be parallel to the lines of the building. A quick and efficient method of attaining this parallelism is found in the adjustable T-square 18 illustrated in Fig. 1. This adjustable square includes a horizontal foot 19 long enough to span three nails with a centering notch formed in the middle. A vertical leg 20 is pivoted directly above the centering notch and any suitable means, such as a brace 21, is provided for holding the parts in adjusted position. The under side of the vertical leg 20 is provided with a plurality of projecting points 22 spaced the same distance apart as the distance desired between horizontal rows of nails.

75 In adjusting the square for this particular

building, the horizontal foot is placed over the nails 23, 24 and 25 with the centering notch over nail 24. The distance from the center of nail 24 to the corner of the building is then measured and the vertical leg of the square is adjusted so that the center of the top point 22 is this same distance from the corner of the building. The brace 21 is then fastened and the square is maintained in this adjusted position while this wall of the building is being finished.

10 After the vertical leg 20 has been secured in proper angular relation, it is pressed against the tar paper and the points 22 penetrate the paper and indent the sheathing, marking the positions for several nails of the vertical row 17.

15 The T-square 18 is then moved one space to the right, centering over nail 25, and the vertical leg is again pressed against the sheathing to locate the next vertical row of nails. The course of procedure thus outlined is followed until the 20 entire side of the building has been marked.

After a side of the building has been thus marked, or while the marking is still in progress, the nails 13 are driven into the marked holes until the heads 15 meet the sheathing. This marking 25 and nailing is continued over the entire side walls that are to be sheathed before any of the bricks are put in position.

Before laying the lower course of bricks a foundation strip 27 (Fig. 5) is inserted between the 30 sheathing and the foundation. This strip includes a body 28, the rear edge of which is provided with points 29 and upwardly extending attaching lugs 30. The forward edge of the strip is bent upwardly and rolled over to form an inclined edge 31 and a series of holes 32 are formed in the body 28. In applying the foundation strip the points 29 are inserted between the sheathing and the foundation, and the attaching lugs 30 are nailed to the face of the sheathing, so that the 40 body of the strip forms a ledge projecting outwardly from the lower edge of the sheathing. Any suitable mortar, such as a cement mortar, is used to point the bricks, and before laying the lower bricks, a layer of this mortar is first placed 45 on the top of the foundation strip. One of the bricks is then placed on top of the mortar, with the wide face of the brick against the sheathing, and is pressed downwardly into the mortar, the surplus mortar that passed out over the space 31 50 and downwardly through holes 32 being subsequently removed.

The upper edge of the brick is now secured in place by slipping a secondary anchoring device or retaining clip 33 over each of the nails above 55 the brick. These retaining clips can be of any desired construction that will give them a tapered shape and permit them to slide vertically under the head of nail in order to adjust themselves to the position of the brick.

60 The preferred form of retaining clip is formed from a single length of rust-resisting wire having a certain amount of resilience. The opposite ends of the wire are bent to form two trapezoidal frames which are disposed with their long sides 65 parallel to each other and spaced apart a distance slightly less than the diameter of the nail shank. The narrow sides are farther apart and are connected by the central part of the wire 35. In fastening the clip in place the open side of the 70 clip opposite the wire part 35 is passed over the shank of the nail, the long sides of the trapezoidal frames being spread apart to resiliently grip the shank of the nail. The clip is of such height as to fit snugly between the head of the nail and 75

the sheathing, and the sides of the trapezoidal frames are formed on an angle corresponding to the angle of bevel of the edges of the brick. As the clip is pushed down over the nail from the dotted line position 36 to Fig. 2 to the full line position, the sides of the clip closely engage the edge of the brick.

After the first course of brick has been laid and secured in position by the clips, a layer of mortar 10 is laid along the top edge of that course.

In laying the second course of brick, a brick is first placed in a tilted position with its lower inner edge in contact with the tar paper, and this lower corner is then pushed downwardly along the tar 15 paper to scrape the mortar down into the joint between the two bricks. The upper edge of the brick is then pressed inwardly against the tar paper as shown by the arrow 37 of Fig. 2, and clips are engaged with the upper edge of the 20 brick. The excess mortar that has been pressed out between this brick and the one below it is then cut off and the pointing is smoothed off as desired. It will be clear from Fig. 2 that the clip acts as a keystone-shaped wedge engaging the 25 bevelled faces of the bricks to lock them securely in place.

Due to the fact that all nails are driven before the laying of bricks commences, there is no hammering that might loosen or dislodge any of 30 the mortar during the laying of the bricks.

After the mortar sets it is permanently held in place by reason of its interlock with the wire clip. However, if desired, additional means may be used to lock the mortar in place as, for example, 35 the grooves 38 shown in Fig. 7. Or the rear edges of the bricks may be formed with rearwardly formed bevels 39 shown in Fig. 6, the rear edges of the bricks being maintained intact between the bevels in order to locate the bricks on the nails.

40 The brickwork can be carried around the corner of the building by providing special angular shapes or by filling the corner with mortar in any desired manner.

The method of laying out the nails described 45 above is used for regular course work. Wherever it is desired to lay the brick in herringbone or other fancy designs, special paper carrying a printed pattern can be placed on the building to guide in the location of the nails and bricks, and 50 while the invention has been described as applied to give the appearance of ordinary brickwork, the size and shape of the veneering pieces can be altered as desired to imitate any natural raw material or to express original ideas in wall finish.

55 It will be clear to those skilled in the art that this brick veneering can be applied by ordinary unskilled labor in a very expeditious manner. The resulting construction is such that each individual brick is attached directly to the sheathing 60 and is supported by several nails. Should water seep through any of the joints in the brickwork it will run down over the face of the tar paper and will drop out in front of the foundation instead of being retained on top of the foundation 65 to rot the sill, as is the case of ordinary veneer construction. Other advantages of the invention along the lines of economy and improved construction will be apparent to those skilled in the art.

70 In the embodiment shown in Figs. 8 and 9, use is made of facing units having edge formations somewhat different from the formation shown in the previous figures. In these latter figures, 40 indicates a building unit which may be of the 75 same general size and dimensions as the brick

previously described. However, the longitudinal edges of these units, instead of being bevelled, are provided with triangular-shaped grooves 41, intermediate the front and rear surfaces thereof. The rear edges of the longitudinal expanses of 5 the unit are rounded as shown at 42.

In the application of units, as shown in these figures to supporting structure, use is made of foundation strips 27 in general similar to those previously described; and primary anchoring 10 means or double-headed nails 13 similar to those previously described. However, a different type of secondary anchoring means or wire clip is used. As shown in Fig. 13, this wire clip is made from a single length of wire shaped to have a loop 15 portion 44 extending into upright expanses 45, slightly bowed at their extremities, such portions having parallel expanses 46 as continuations thereof, with the ends of these expanses turned back, as shown at 47 with the ends of the wire 20 adjacent the ends of the loop 44.

Use also may be made of the instrument shown in Fig. 1 for determining the positions of the primary anchoring means, or use may be made of the instrument shown in Figs. 8 and 10 to 12, 25 inclusive. The latter instrument comprises a base bar 50 to which is secured an arc-shaped member 51. A portion of this arc-shaped member is provided with a slot 52 pivotally secured to the base bar 50. Midway between the ends 30 of the member 51 is a bar 54. Bar 54 is provided longitudinally thereof with a number of spaced slots 55 for the accommodation of indicating means. The indicating means comprises a bolt-like member 56 having an enlarged disc 35 head 57 terminating in a point 58. The other end of the member 56 is threaded for the reception of a nut 58'. The member 56 passes through one of the slots 55 with the head 57 resting against one surface of the bar 54 and with the nut 58 40 resting against the other surface of this bar. Since the slots 55 are of relatively considerable length, it follows that the indicating members secured to the bar in the various slots can be adjusted within limits to accommodate variations 45 in size of facing units. The lower end of the bar 54 is provided with a notch 59 adapted to engage one of the primary anchoring means for proper alignment of the vertical series of anchoring means. A bolt and nut arrangement 59' 50 passing through the slot 52 and the bar 54 permits the bar 54 to be locked in any desired angular position, as shown in broken lines (Fig. 8).

The method of application of the facing units shown in Figs. 8 and 9 is substantially the same as that previously described, in that the primary anchoring members or nails 13 are first driven into the sheathing of the supporting structure through the tar paper or other insulation. The desired positions of these nails may be determined by use of the instrument shown in Fig. 8. The various points 58 associated with this instrument when pressed into tar paper leave indications for the proper positions of the nails. With the foundation strip 27 in place, a layer of mortar is placed on top of this strip and then the facing units or brick of the first course are pressed into the top of the layer of mortar until the units have become firmly set. In this position the top edges of the units are spaced some distance from the first horizontal row of nails 13. As each individual unit is placed in proper position, relative to the foundation strip, it is secured in place by the secondary anchoring means or clips shown in Fig. 13. Due to the construction of the clips and 70 75

the provision of the considerable space between the top of the units and the nails 13, the clips can be positioned with the loops 44 thereof resting directly on the nail adjacent the inner head thereof and with the parallel expanses of the clips on each side of the nail and under the outer head thereof. In this position as shown in Fig. 9 the tips of the bent-back portions 47 become firmly seated in the triangular-shaped grooves 41, extending longitudinally of the top edge of the units. After the first course of units has been laid with the proper spacing between the ends thereof and with the secondary anchoring means or clips in place, the next course of units can be laid. Prior to the application of any unit, however, a layer of mortar is applied to the top of the units in the first course; the amount of mortar being estimated to provide an excess beyond that needed. The units of the second course may then be placed in position, the lower edge of each unit being forced against the layer of mortar until the bottom contacts with the upper part of the clips, in which position the upstanding part of the bends 45 protrude into the recess 41 in the lower edge of the unit. When properly positioned it will be seen that the lower edge of the unit rests against the loop 44 of a clip and, since this loop 44 is in direct contact with the nail 13, it follows that the unit is almost directly supported by the nail. As the unit is pressed downwardly until properly seated, the excess amount of mortar is extruded from between the adjacent units and such excess can be removed and the joint pointed in the customary fashion. Successive courses of brick or units can be laid until the structure has been completed.

Figures 14 and 15 illustrate the manner in which the present invention can be used in the construction of tile walls and the like. In these figures, 60 indicates facing units or tiles of conventional dimensions and differing from conventional tilting only in that recesses 61 are provided in certain of the edges of the units, preferably in the longitudinal edges thereof. As shown in the drawings, each recess has an inwardly extending wall 62 substantially parallel with the faces of the unit, and with a bottom wall 64 of curvature approaching ogee form. This curved wall of the recess extends from the wall portion 62 to the opposite face of the unit. The secondary anchoring means or clips used in this construction are shown clearly in Fig. 16, wherein the clips indicated generally at 65 are made of a single strip of wire having a loop 66, legs 67 of partial ogee curvature forced into close proximity, and leading into loops 68 at right angles to the loop 67. The end portions of the wire are also of partial ogee curvature as shown at 69, and the ends of the wire are spaced from the loop 66.

60. In the practice of the present invention in connection with the construction of tile walls and the like, the same procedure is followed in the first stages as previously set forth, in that the primary anchoring means or nails are fastened to the supporting structure in the predetermined positions and, if desired, a foundation strip may be attached to the same structure. After the first course of units or tiles have been placed in position, the individual tiles may be locked to the supporting structure by the secondary anchoring means or clips. These clips are secured under the outer head of the various nails 13 with the outer head engaging the edges of the loops 68 and positioned substantially midway of the extremities of these loops. When so engaged

with the nails the end portions 69 of the clips make good contact with the curved wall of the recess 61. After the first course of tile has been properly positioned and the secondary anchoring means applied, mortar or cement may be placed in such quantity as to completely fill the upper recess of each unit and as to provide an excess. Tiles of the second course may then be applied by pressing the same downwardly against the mortar or concrete until the grooved wall of the 10 recess in the lower edge of each unit contacts with the curved expanses 67 of the clip. When such contact has been made it will be found that the superimposed tiles are spaced apart a very slight amount as shown at 70, such space serving 15 to receive the finishing cement or mortar. Any excess of mortar from the union of recesses can be removed with a suitable thin tool to condition the joint 70 for the reception of the finishing material.

20 By this arrangement it will be apparent that the usual objections found to the conventional methods of applying tile are overcome. Instead of depending upon a cement bond between the tile and the supporting structure, each tile is 25 effectively anchored directly to the supporting structure.

25 In Figs. 17 to 20, inclusive, the use of the invention in connection with the construction of double walls has been shown. In these figures, usual 30 sheathing or siding has been omitted since it is contemplated that the uprights alone will suffice. Referring particularly to Fig. 17, 80 indicates the top of the foundation on which rests a sill 81 having uprights 82 secured thereto. The uprights 82 35 are spaced apart any desired predetermined distance.

35 The facing units especially adapted to be used in this construction are of such length as to extend substantially from the mid-point of one 40 upright to the mid-point of a second upright spaced from the first. By this arrangement it is possible to have the usual staggered arrangement of units. The units which are illustrated at 84 have their longitudinal edges provided with 45 substantially triangular-shaped recesses 85. The exact form however of these recesses can be varied to meet various conditions. In conjunction with units of this character, use is made also of the same type of primary anchoring means or 50 nails 13, and secondary anchoring means or clips 65 similar to those described in connection with Fig. 16. However, if the shape of the grooves in the facing units should be changed, other shapes of clips can be adapted to conform thereto.

55 In the installation of units, as shown in Figs. 17 to 20, the lower units are embedded in mortar placed directly on top of the foundation 80, with the rear faces of the units in contact with the sill 81. The primary anchoring means 13 of course are secured to the uprights in pairs, as shown, prior to the laying of any unit. The first course of units are laid in the usual manner, each unit being locked in place by the addition of a secondary anchoring means or clip engaging one of the nails 13 and having a portion of the clip seated in the proper groove 85 of the unit. The anchoring means are positioned on the uprights in pairs so that adjacent ends of units can be 70 anchored respectively by the clips of each pair with the clips on an intermediate upright serving to hold the intermediate portion of the unit in place. After the first course of units has been applied, mortar can be placed on top of the units 75

rendering the first course ready for the reception of a second course.

This type of construction is particularly adapted for the construction of double walls and, accordingly, as shown in the drawings, such double wall construction can be made by adding courses both to the outside of the wall and to the inside of the wall uniformly so that the wall progresses upwardly in uniformity. As an auxiliary feature it is contemplated that spacing and bonding straps 90 may be utilized in conjunction with this construction. These straps 90 are made of metal of suitable gauge having each end with split parts thereof bent at right angles as shown at 91, and the other parts thereof bent into substantially hook shape as shown at 92. As each course of units is laid and locked in place by the clips, straps 90 can also be installed with the angular portions 91 extending either upwardly or downwardly, as may be desired, and with a portion of the hooked parts 92 resting in the respective grooves 85. After mortar has been placed, a second course of units can be laid with the result that the remaining or opposite part 25 of the hook portions 92 extend into the grooves 85 in the bottom edges of the superimposed units. With this construction a unitary wall, double in character, results. The advantage residing in the use of the straps 90 is that the unitary character of the double wall is maintained even though the utility of the uprights be impaired for any reason, such as dry rot and the like.

Unitary double walls of this character are adapted for use both as outer walls of building structures and also as inner walls. The units may be made of any desired material, such as stone, pre-formed compositions of concrete and the like, or other pre-formed composition material. The only requirement is that the units be of proper size, shape and configuration, particularly with respect to the provision of properly shaped recesses in the longitudinal edges. While the construction shown in Figs. 17 to 20 deals primarily with double wall constructions it will be apparent that single wall constructions, omitting the straps 90, can be erected with equal facility. In the double wall construction however space between the two vertical walls serves as a good thermal insulation space and, if desired, thermal insulation material can be packed into such space.

Fig. 22 illustrates the manner in which substantially rounded corners can be procured in the practice of this invention. In this figure, 100 represents an upright one corner of which is cut away as shown at 101. Units 102 are secured to right angular faces 104 of the upright by the anchoring means previously described in any desired manner, it being understood that the grooves in the edges of these units can be of configuration corresponding to that shown in any of the embodiments, or of any other desired configuration with the clips having shapes conformed thereto. In order that the space between the ends of the units 102 can be filled in and the construction given a somewhat rounded character, use may be made of units 105 which are of substantially truncated wedge shape. These units have grooves corresponding to those in the other units and are held in place by anchoring means in the same fashion. Mortar 106 of course is applied between the respective ends of the units 102 and the vertical edges of the unit 105.

From the foregoing it will be seen that the present invention in any phase thereof provides novel

and efficient methods for applying pre-formed facing material to supporting structures. Brick veneer work can be installed at greatly reduced cost relative to the cost of conventional type of brick veneering. Skilled labor is not required in the practice of the methods set forth herein since, if proper steps are followed, these methods can be practiced with ease. The installation of tile in walls and the like can be accomplished at greatly reduced cost and the resulting structure is more durable than structures erected in conventional manners. Moreover, as pointed out hereinbefore, unitary double wall constructions can be erected with a minimum of labor and expense.

The term units as used herein is to be construed as covering preformed blocks of any desired composition, such as clay products, concrete, ceramic material, glass, and any other composition that lends itself to use in building construction.

It is to be understood that the invention can be modified beyond the illustrated embodiments in view of which any limitations imposed thereupon are to be such only as are set forth in the following claims.

I claim:

1. The process of laying a veneer over a frame building which comprises driving nails into the sheathing of the building at predetermined intervals, laying pieces of veneering material between the nails, securing the said pieces by clips, and covering the clips with mortar placed in the joints between the said pieces.

2. The process of laying a brick veneering over a frame building which comprises driving nails into the sheathing of the building in rows at predetermined intervals, thereafter laying veneering bricks between the nails, securing the bricks by clips engaged with the nails, and covering the clips with mortar placed in the joints between the bricks.

3. The process of laying a brick veneering over a frame building which comprises inserting rows of nails in the sheathing of said building in parallel horizontal and vertical rows, the nails being spaced from each other distances appropriate for cooperation with veneering bricks, thereafter laying veneering bricks between the nails, securing the bricks by clips engaged with the nails, and covering the clips with mortar placed in the joints between the bricks.

4. The process of laying a veneer over a frame building which comprises covering the frame with sheathing boards, covering the boards with sheet material, driving nails into the sheathing at spaced intervals, laying pieces of veneering material between the nails, securing the said pieces by clips, and covering the clips with mortar placed in the joints between the said pieces.

5. The method of applying pre-formed facing units to supporting structure, which comprises securing primary anchoring devices to said supporting structure at predetermined intervals, laying said units between primary anchoring devices, locking said units to said supporting structure by secondary anchoring devices engaging the primary anchoring devices and cooperating formations in said units and by bonding material between adjacent edges of adjacent units.

6. The method of applying pre-formed facing units to supporting structure, which comprises securing nails to said supporting structure at predetermined intervals, laying said units between nails, locking said units to said supporting structure by clips engaging the nails and cooperating

70
75

formations in said units and by bonding material between adjacent edges of adjacent units.

7. The method of applying pre-formed facing units to supporting structure, which comprises securing nails to said supporting structure at predetermined intervals, laying an initial course of said units between a foundation and certain of said nails with bonding material between the adjacent ends of said units, locking said units to said supporting structure by clips engaging the nails and cooperating formations in said units, applying bonding material to the top edges of said units, and applying successive courses of units in like fashion.

15 8. The method of applying tiles having grooves in certain of the edges thereof to supporting structure, which comprises securing primary anchoring devices to said supporting structure at predetermined intervals, laying said tiles between said primary anchoring devices, and locking said tiles to said supporting structure by secondary anchoring devices partially engaging said primary anchoring devices and partially fitting in said grooves and by bonding material interposed between adjacent edges of adjacent tiles to fill adjacent grooves thereof with relatively narrow spaces between the ungrooved edge portions of said tiles.

9. The method of applying tiles having grooves in certain of the edges thereof to supporting structure, which comprises securing nails to said supporting structure at predetermined intervals, laying said tiles between said nails, and locking said tiles to said supporting structure by clips partially engaging said nails, partially fitting in said grooves and by bonding material interposed between adjacent edges of adjacent tiles to fill adjacent grooves thereof with relatively narrow 10 spaces between the ungrooved edge portions of said tiles.

10. The method of applying pre-formed facing units to spaced upright supporting members, which comprises securing primary anchoring devices to said upright supporting members at spaced intervals, laying initial courses of said units upon a foundation and on each side of said supporting members, locking said units to said supporting members by clips engaging the nails 15 and cooperating formations in the units and by bonding material, inserting spacing straps between the units of the respective courses to be embedded in said bonding material, and superimposing additional courses upon the initial 20 courses.

ALFRED H. PARSONS.
